UNITED STATES PATENT OFFICE

HARRY CLEVELAND SMITH, OF NEW YORK, N. Y., ASSIGNOR, BY MESNE ASSIGNMENTS, TO AUTODRINK CORPORATION, OF DOVER, DELAWARE, A CORPORATION OF DELAWARE.

BEVERAGE-DISPENSING DEVICE

Application filed August 25, 1927. Serial No. 215,485.

This invention relates to beverage dispensers, and more particularly to dispensers of the visible type.

To that end the invention contemplates a novel and practical display unit which permits of attractively displaying the beverage to be sold so that the purchaser will not only be able to see what he is obtaining but will also be attracted by the display. In that connection the invention contemplates a construction wherein the beverage to be sold is caused to fall from a higher level to a lower level in the form of a cascade, thereby insuring proper agitation to cause the pulp or other heavier parts of the beverage of some fruit juices to be properly mixed and kept in circulation.

A further object of the invention is to provide a cascading unit which lends itself to various modifications and also renders various lighting effects practical and feasible, thereby greatly enhancing the attractiveness of the display.

With the above and other objects in view which will more readily appear as the nature of the invention is better understood, the same consists in the novel construction, combination and arrangement of parts hereinafter more fully described, illustrated and claimed.

A preferred and practical embodiment of the invention is shown in the accompanying drawings, in which:—

Figure 1 is a perspective view of the transparent dispensing portion of the device.

Figure 2 is a vertical sectional view of the unit shown in Fig. 1 together with the source of supply and the piping circuit for maintaining the proper circulation of the beverage.

Figure 3 is a vertical sectional view of a modified form of dispensing unit.

Figure 3^a is a detail perspective view of a conical type of cascade unit shown in Fig. 3.

Figure 4 is a perspective view of a pyramidal form of cascade member.

Figure 5 is a vertical sectional view of a plain form of cascade unit.

Similar reference characters designate cor-

responding parts throughout the several figures of the drawings.

In carrying the present invention into effect it is proposed to provide a transparent dispensing container or casing designated generally as A which may be of any desired shape or form and mounted upon a base B, the latter having associated therewith an overflow pipe B' for establishing a residual beverage level indicated by the dotted line in Figs. 2 and 3. The pipe B' is also provided with a drain port or bleed hole x which permits the residual beverage to drain back to the supply when the pump is cut off and also permits a part of the trapped beverage to continually make its way back to the tank to keep it properly cooled.

Within the transparent container A there is provided a novel cascading unit designated generally as C, and which in its primary aspect includes a body portion provided with a plurality of steps, ribs, shoulders or riffles 1 having at the upper end thereof a supply well 2. The body portion of the cascade member C may be formed of translucent or transparent material and the well 2 may be formed integrally with the body as shown, or separately without departing from the spirit of the invention. In its essential characteristics however, the body of the cascade member is preferably inclined and has the supply well 2 at its upper end while its lower end preferably reaches to or below the level of residual beverage in the container, as shown.

By way of illustrating the wide range of modification of the essential features above described, reference may be made to Figs. 3, 3^a and 4 from which it will be observed that the transparent dispensing unit A' houses and conceals a conical cascade member C' also of stepped formation. In this form the steps 1^a are continuous circular shoulders or riffles while the well 2^a at the top is circular.

Figure 4 illustrates a pyramidal form of cascade member C^b, the steps or shoulders 1^b in this form being also continuous but angularly related, while the well 2^b at the top of the unit is also preferably rectangular.

All forms of the invention are readily

adaptable to novel lighting effects as will be apparent from the drawings.

Figure 2 for example shows a lamp L located at the rear of the cascade member C, while Fig. 3 illustrates a pair of lamps L² supported from the base B² of the transparent dispensing unit A'. Obviously different colored globes may be used in the lamp sockets thereby to materially enhance the attractiveness of the display and the lamps may be caused to burn continuously or intermittently in accordance with well known electrical practices in that connection.

In all forms of the invention the transparent dispensing units are provided with dispensing nozzles or faucets D which tap the supply of liquid held in the dispensing unit through the medium of the overflow pipe B'.

In that way the customer is able to see exactly what he is buying, and of course since the beverage is maintained continuously in circulation a properly cooled as well as fresh drink will always be supplied from the faucet.

Referring briefly to the means for supplying the beverage to the cascading until it will be observed that a supply container E may be located at any convenient point below the dispensing unit A, the same being preferably iced or cooled by natural ice or cooling coils of the automatic refrigeration type now widely in use, and having a feed or supply pipe designated generally as F into which the beverage is pumped from the bottom of the container by means of a suitable motor driven pump G. The feed pipe F may be provided with a flexible connection F' leading to the supply pipe F² projecting upwardly through the overflow pipe B' and connecting with the well 2 of the cascade member. The overflow pipe B' may be connected at its lower end by the flexible connection B³ or its equivalent with the discharge of the container E thereby to empty the excess of beverage from the predetermined level in the dispensing unit back into the supply container so that a continuous circuit is provided.

In the form of apparatus shown in Fig. 3 the same circulating connections are employed to connect the well 2^a with the source of the supply, and therefore further reference to these features will not be made.

From the foregoing it will be apparent that a novel and distinctive feature of the present invention resides in pumping or forcing beverage from a lower level to the well of a cascading unit so that the beverage will flow from the well or trough downwardly over the riffles or steps and produce a novel cascading effect. Clearly it is within the scope of the present invention to vary the shape, size and form of the projections or steps 1 without departing from the scope of the invention.

Also, as will be observed from Figure 5 of the drawings a plain type of cascading unit may be used. This member is transparent or translucent and responds to all of the functions and requirements of the other cascading units although it does not involve a series of projections or steps of the type shown in the other forms of the invention.

Without further description it is thought that the features and advantages of the invention will be readily apparent to those skilled in the art, and it will of course be understood that changes in the form, proportion and minor details of construction may be resorted to, without departing from the spirit of the invention and scope of the appended claims.

I claim:—

1. A dispensing device of the class described including a transparent container, an inclined member within said container, means for supplying beverage to the upper portion of said member to permit it to flow downwardly thereover, and means for dispensing liquid from the container.

2. A dispensing device of the class described including a transparent container, a cascade member having projections thereon and arranged within the container, and means for supplying beverage to the upper edge of said cascade member whereby the same will flow downwardly over the projections thereon, and means for dispensing liquid from the container.

3. A dispensing device of the class described including a transparent container, a cascade member having a plurality of horizontally disposed projections thereon and said cascade member being arranged within the container, and means for supplying beverage to the upper edge of said cascade member whereby the same will flow downwardly over said horizontal projections, and means for dispensing liquid from the container.

4. A dispensing device of the class described including a transparent container, a translucent cascade member including a body portion having an inclined wall said member being arranged within the container, means for supplying beverage to the upper edge of said wall whereby the beverage will flow downwardly thereover, and means for dispensing liquid from the container.

5. In a device of the class described, a cascade member having a plurality of steps thereon, a transparent container for said cascade member, a well formed at the top of said member, means for supplying beverage to said well, and means for dispensing liquid from the container.

6. A device of the class described, including a transparent casing, a translucent cascade member having a plurality of steps thereon and arranged within the container, a well formed at the top of said translucent

member, means for supplying beverage to said well, and means for dispensing liquid from said transparent casing.

7. A dispensing device of the class described including a transparent dispensing bowl, a stepped member arranged within the bowl, overflow means within the bowl and means for continuously causing beverage to cascade over said stepped member.

10. A dispensing device of the class described including a transparent dispensing bowl, a translucent cascade member arranged within the bowl having projections, means for directing beverage in a continuous flow over the cascade member, and means for illuminating the cascade member.

15. A dispensing device of the class described including a transparent dispensing casing, a translucent cascade member arranged within said dispensing casing, and means for supplying beverage to the upper edge of said member whereby the beverage will flow downwardly thereover, and means for dispensing liquid from said casing.

20. 10. In a dispensing device of the class described, a transparent dispensing container, an inclined cascading member arranged within said dispensing container, means for flowing a beverage over one side of said inclined member, means for illuminating said member, and means for dispensing liquid from the container.

25. 11. In a dispensing device of the class described, a transparent dispensing container, an inclined translucent member arranged within said dispensing container, means for coursing a beverage over one side of said inclined member, means on the other side of said member for illuminating the same, and means for dispensing liquid from said container.

30. 12. In a dispensing device of the class described, including a transparent dispensing container, an inclined translucent member having projections thereon, means for supplying beverage to the side of the inclined member having the projections, a source of light on the other side of said inclined member for illuminating the projections and the beverage flowing thereover, and means for dispensing liquid from said container.

35. 13. In a dispensing device of the class described, a transparent bowl, a translucent cascade member having projections thereon arranged within the bowl, said member being of substantially conical form, overflow means in the bowl, means for supplying beverage to the upper part of said cascade member whereby it will flow downwardly thereover into the bowl to the level of the overflow means, illuminating means within the cascade member, and means for dispensing liquid from the transparent bowl.

40. 14. In a dispensing device of the class described, the combination with transparent

45. container providing a display well, of a source of light within the container above the level of the well, a cascade member masking said source of light, means for coursing beverage over said cascade member, and means for dispensing liquid from the display well.

50. 15. In a device of the class described, a transparent dispensing casing, overflow means therein providing a well, means for dispensing liquid from said well, a source of light arranged within the casing, a cascade member masking the source of light, and means for supplying beverage to the cascade member.

55. 16. In a dispensing device of the class described, a transparent casing, an inclined translucent member enclosed within the transparent casing, means for illuminating the translucent member, means for causing a beverage to flow downwardly over the face of the translucent member, and draw-off means for the beverage.

60. 17. A device of the character described including a dome-like body, a transparent hood spaced over the body, and means operating to circulate liquid between the dome and body.

65. 18. A device of the character described, including a dome-like body, a transparent hood spaced over the body, a bottom supporting the body and hood and having a drain opening, and means for delivering liquid to the top of the body to circulate between the body and hood and discharge through the bottom.

70. 19. A device of the character described, including a transparent dome-like body, a transparent hood spaced over the body, means for delivering liquid to the top of the space between the body and hood, and means for illuminating the interior of the body.

75. 20. A device of the character described, including a dome-like body, projections on the exterior of the body, a transparent hood spaced over the body, and means operating to circulate liquid between the dome and body.

80. 21. A device of the character described, including a dome-like body, a transparent hood spaced over the body, an annular bottom supporting the body and hood and having a drain opening, and means for delivering liquid to the top of the body to circulate between the body and hood and discharge through the bottom.

85. In testimony whereof I hereunto affix my signature.

HARRY CLEVELAND SMITH.
